UNITED STATES PATENT OFFICE.

HARRY M. HALDEMAN, OF INDIANAPOLIS, INDIANA, ASSIGNOR OF ONE-HALF TO THE McELWAINE-RICHARDS COMPANY, OF SAME PLACE.

DESIGN FOR A BOWL FOR WATER-CLOSETS.

SPECIFICATION forming part of Design No. 33,642, dated December 4, 1900.

Application filed October 17, 1899. Serial No. 733,927. Term of patent 14 years.

To all whom it may concern:

Be it known that I, HARRY M. HALDEMAN, of 2246 West Washington street, in the city of Indianapolis and State of Indiana, have 5 invented and produced a certain new and original Design for Bowls for Water-Closets, of which the following is a description, referring to the accompanying drawings.

The design is especially applicable to jail-closets.

Figure 1 is a side view. Fig. 2 is a section. Fig. 3 is a rear perspective, and Fig. 4 is a plan view.

The design is fully shown in the figures. 5 From the base or foot the fixture at first contracts and then expands upward laterally, being considerably wider at the oval seat-rim, as seen in Figs. 3 and 4, while in side view an extremely simple smooth exterior is presented. The hollow anchorage or base portion is both flared and of increased thick-

ness of wall, as shown. The combined overflow and discharge passage D rises from the bowl of the fixture and enlarges slightly from the bowl toward the point where it terminates 25 in the flat connecting-flange, as shown. The lowest point of the overflow-opening O is about an inch and a quarter above the level of point P. The rim is rounded and not angular and forms the seat, as well as a flush- 30 ing-rim, leaving the whole design extremely simple.

What I claim is—

The design for a bowl for water-closets as described and illustrated.

Signed this 26th day of August, 1899, at Indianapolis, Indiana. 35

H. M. HALDEMAN.
